UNITED STATES PATENT OFFICE.

ALFRED MORELL, OF WORCESTER, MASSACHUSETTS, ASSIGNOR TO CROMPTON & KNOWLES
LOOM WORKS, A CORPORATION OF MASSACHUSETTS.

WEFT-REPLENISHING LOOM.

No. 880,810.

Specification of Letters Patent.

Patented March 3, 1908.

Application filed December 1, 1906. Serial No. 345,863.

To all whom it may concern:

Be it known that I, ALFRED MORELL, a citizen of the United States, residing at Worcester, in the county of Worcester and 5 State of Massachusetts have invented certain new and useful Improvements in Weft-Replenishing Looms, of which the following is a specification.

My invention relates to weft replenishing 10 looms, and to the filling transferring mechanism thereof, and more particularly relates to the trip or dagger carried on the transferrer arm of the transferring mechanism.

The object of my invention is to improve 15 upon the ordinary construction of the trip or dagger carried on, or connected with the transferrer arm, and which is adapted, on the practical exhaustion of filling, to be moved into the path of and be engaged by 20 the bunter on the lay, on the forward movement thereof, to cause the movement of the transferrer arm, to engage and transfer a fresh bobbin from the magazine into the active shuttle, to take the place of the practically exhausted bobbin in said shuttle.

In the ordinary construction of the trip or dagger connected with the transferrer arm, there is no yielding or give-way movement of said dagger, independent of the transferrer 30 arm, when said dagger is moved into position to be engaged by the bunter on the forward movement of the lay, and if for any reason a bobbin which is to be discharged from the magazine and pushed into the shuttle by the 35 transferrer arm, is not in proper position to enter the shuttle and push out the old bobbin therein, but is prevented from so doing, then the transferrer arm being forced down by the engagement of the bunter with the 40 dagger or trip on the transferrer arm, on the forward movement of the lay, some part of the mechanism must give way or break.

In my improvements, I provide a yielding or give-way device connected with the trip 45 or dagger, which is attached to the transferrer arm, and which in the normal operation of the loom will remain in a predetermined fixed position to receive the impact of the bunter on the forward movement of the lay, 50 and cause the movement of the transferrer arm in the usual way, to transfer a bobbin from the magazine into a shuttle, but in case the bobbin is prevented from entering the shuttle when the transferrer arm is operated,

or there is any obstruction to the downward movement of the transferrer arm, then said device will yield or give way on the engagement of the bunter therewith, without causing the complete movement of the transferrer arm, and thus preventing any breaking of 60 the parts.

I have only shown in the drawing a detached portion of the weft replenishing mechanism of a weft replenishing loom, having a stationary magazine, with my improvements 65 combined therewith, sufficient to enable those skilled in the art to understand the construction and operation thereof.

Referring to the drawing:—Figure 1 is an end view of a detached portion of a stationary 70 magazine, and a weft replenishing or transferring mechanism, and a sectional view of the lay-beam in its forward position, and of a shuttle on the lay-beam, showing the several parts in their relative positions, after the 75 transfer of a bobbin from the magazine has been completed. Fig. 2 corresponds to Fig. 1, but shows some of the parts in a different position, and the bobbin from the magazine, prevented from entering the shuttle. Fig. 3 80 is, on an enlarged scale, an inner end view of the trip or dagger shown in Fig. 1, detached, looking in the direction of arrow *a*, same figure. Fig. 4 is a view of the parts shown in Fig. 3, looking in the direction of arrow *b*, 85 same figure. Fig. 5 is a section, on line 5, 5, Fig. 3, looking in the direction of arrow *b*, same figure, and, Fig. 6 shows some of the parts shown at the left in Fig. 2, in another position.

In the accompanying drawing, 1 is a detached portion of the loom frame or end, 2 is a detached portion of a stand secured thereon, which is adapted to support a stationary magazine or bobbin holder 3, only the lower 95 part of which is shown. The magazine 3 is in this instance of the stationary type, having four vertically extending guideways or compartments for four sets of bobbins 4, and means for holding the lowest bobbin in each 100 guideway or compartment in position ready to drop down by gravity into a position at the lower discharging end of the magazine, where it will be engaged by the transferrer arm, and moved through the opening at the 105 lower end of the magazine, and transferred into the shuttle, in the usual way. 5 is the lay-beam showing a portion of the lay sword

6, and 7 is a portion of the shuttle box on the lay-beam. 8 is a shuttle, having a bobbin 4 therein. On the front of the lay beam 5 is carried a bunter 9. The transferrer arm 10 is pivotally mounted on a stud 11, and has an engaging end 10' thereon, which engages a bobbin 4, and a downwardly extending arm 10" thereon carrying a stud or pin 12, on which is pivotally mounted a trip or dagger 13. A spring 14 acts to raise and hold the transferrer arm 10 in its raised position, and a spring 15 acts to move the trip or dagger 13 into its raised position, and into the path of the bunter 9, when the arm 13' thereon is released by the hook connector 16, adjustably connected to the lower end of a lever or arm 17, the hub of which, not shown, is pivotally mounted on the stud 11, and has an extension thereon which is connected 20 through intermediate mechanism with the filling detector or indicating mechanism, not shown, at the opposite end of the loom, in the usual and well known way. All of the above mentioned parts, except the trip or dagger 13, may be of the usual and well known construction in weft replenishing looms of the class referred to.

I will now describe my improvements in the trip or dagger 13, which is provided with 30 a yielding or give-way device to be engaged by the bunter, and which will on the extreme forward movement of the lay, yield or give way, when engaged by the bunter, allowing the trip or dagger 13 to move down 35 to its lowered position, out of the path of the bunter, and permit the transferrer arm 10 to remain stationary, without completing its downward movement, in case the bobbin to be transferred is not in proper position to 40 enter the shuttle, or there is any obstruction to the downward movement of the trans- ferrer arm 10.

The trip or dagger 13 comprises as a part thereof, in this instance, a plate or bar 13', having a beveled inner end 13", and a beveled shaped extension 13''' thereon, see Fig. 3, to extend into a corresponding recessed portion in the trip or dagger 13, and be adjusted therein in the direction of the length 50 of the plate 13', by a set screw or bolt 18, see Fig. 5, which turns in a threaded hole in the trip or dagger 13. The plate or bar 13' is secured in adjusted position by a bolt 19, see Fig. 3. The plate or bar 13' has thereon a 55 boss or rounded portion 13^a, see Fig. 4, to receive a longitudinally moving pin 20, which has its engaging end 20' beveled, or of wedge shape, and has the reduced portion 20" to receive a helically coiled expansion 60 spring 21, which extends within the boss 13^a, and bears at one end against the end thereof, and at its other end against the enlarged end of the pin 20, see Fig. 5. A nut 22 on the screw threaded end of the pin 20 is used to 65 adjust the pin 20 within the boss 13^a, to

regulate the tension of the spring 21, and a second nut 23 acts as a lock nut.

The inner beveled end of the plate or bar 13', with the beveled head 20' of the spring actuated pin 20, forms a beveled recess to receive the beveled end of the bunter 9, as shown in Fig. 1, and the beveled engaging end of the bunter 9 is of such a shape, relative to the beveled recess formed by the beveled end of the plate 13' and the beveled end of the pin 20, that in the normal operation of the loom and the transferrer mechanism, the bunter, as the lay moves forward will engage and remain in the beveled recess at the inner end of the dagger or trip 13, and move back- 70 wardly the transferrer arm 10, to engage and transfer a bobbin from the magazine into a shuttle. 75

The pivotal support or fulcrum of the dagger, and the direction of movement of the 85 bunter 9 are relatively such, that the direction of movement of the bunter is in a line which will pass above the pivot of the bunter, so that the dagger cannot move down on its pivot support, and consequently the trans- 90 ferrer arm must move down as the dagger moves backwardly. But if for any reason the transferrer arm 10 is prevented from completing its downward movement, and consequently the dagger or trip cannot be 95 moved backward to its extreme position, then the shape of the beveled engaging end of the bunter 9, relative to the inner end of the dagger 13, is such, that the bunter will push back the pin 20 enough to let the bunter 100 pass by said pin, and allow the dagger 13 to drop to its lowered position, as shown in Fig. 6.

The operation of my improved trip or dagger 13 will be readily understood by those skilled in the art. 105

The spring 21 is of sufficient strength to hold the pin 20 on the dagger 13 in its out- 110 ward position in the normal operation of the loom, with its beveled head 20' in substan- tial alignment with the beveled end 13" of the plate or bar 13', to receive the impact of the dagger 13 on the forward movement of the lay, as shown in Fig. 1, and cause, through the movement of the dagger 13, the downward movement of the trans- 115 ferrer arm 10, to transfer a bobbin from the magazine into the shuttle in the usual way; but in case a bobbin is not in proper position to be transferred from the magazine, so that the transferrer arm cannot complete its 120 movement, then the engagement of the bunter 9 with the dagger 13, on the forward movement of the lay, will as the lay ap- 125 proaches its extreme forward position, move outwardly the spring actuated pin 20, which forms a yielding or give way device for the dagger, and allow the bunter 9 to pass by the dagger 13, as shown in Fig. 2, and allow the dagger 13 to drop down, as 130 shown in Fig. 6, and leave the trans- ferrer

arm 10 stationary, without completing its downward movement, and thus prevent the breaking of any of the parts.

It will be understood that the details of construction of my improvements may be varied if desired, and they may be adapted to be applied to and used with the trans- 5 ferrer arm of magazines of different construction, either stationary or movable.

10 Having thus described my invention, what I claim as new and desire to secure by Letters Patent is:—

15 1. In a transferrer mechanism of a weft replenishing loom, the combination with a bunter on the lay and the transferrer arm, of a trip or dagger connected with the trans- ferrer arm, and having a yielding or give- 20 way part to be engaged and moved by said bunter, on the forward movement of the lay, in case of obstruction to the movement of the transferrer arm.

25 2. In a transferrer mechanism of a weft replenishing loom, the combination with a bunter on the lay, and the transferrer arm, of a trip or dagger connected with the trans- ferrer arm and having a yielding or give- 20 way part to be engaged and moved by said bunter on the forward movement of the lay,

in case of obstruction to the movement of the transferrer arm.

30

3. In a transferrer mechanism of a weft replenishing loom, the combination with a bunter on the lay, and the transferrer arm, of a trip or dagger connected with the trans- ferrer arm and having a yielding or give- 35 way part, said yielding part consisting of a spring actuated longitudinally moving pin, having a beveled end to be engaged by the bunter and moved outwardly.

4. In a transferrer mechanism of a weft 40 replenishing loom, the combination with a bunter on the lay, and the transferrer arm, of a trip or dagger connected with the trans- ferrer arm and having a yielding or give- 45 way part, said yielding part consisting of a spring actuated longitudinally moving pin, having a beveled end to be engaged by the bunter and moved outwardly, said pin having a support adapted to be adjusted on the dagger, to vary the position of the engaging 50 end of the pin relatively to the engaging end of the dagger.

ALFRED MORELL.
